UNITED STATES PATENT OFFICE.

CHARLES ZOOG, OF GARY, INDIANA, AND JOHN MUTCH, OF FAIRPORT HARBOR, OHIO.

ORE-BIN-LOCKING DEVICE.

1,332,373.

Specification of Letters Patent.

Patented Mar. 2, 1920.

Application filed April 11, 1919. Serial No. 289,317.

To all whom it may concern:

Be it known that we, CHARLES ZOOG and JOHN MUTCH, citizens of the United States, and residents, respectively, of the city of 5 Gary, in the county of Lake and State of Indiana, and city of Fairport Harbor, Lake county, Ohio, have invented certain new and useful Improvements in Ore-Bin-Locking Devices; and we do hereby declare that the 10 following is a full, clear, and exact description of the same, reference being had to the accompanying drawings, and to the numerals of reference marked thereon, which form a part of this specification.

15 This invention relates more particularly to an ore bin wherein an improved operating and locking device is provided for the purpose of facilitating the opening and the closing of the bin door for controlling the 20 discharge of ore, coal or other materials stored in the bin and adapted to be delivered by gravity through the door when open, into cars for shipment.

It is an object of this invention to construct an improved operating device for bin doors adapted to be operated to open the doors to permit discharge of material, and furthermore adapted to be readily operated to close the doors against the pressure of 30 the discharging material.

It is also an object of the invention to provide an automatic locking device for the door operating mechanisms of an ore bin.

Another object of the invention is the construction of an ore bin mechanism whereby a bin door is permitted to be opened and closed against the weight of material being discharged through the door opening.

A further object of the invention is the 40 construction of an automatic locking mechanism for a bin door adapted to be manually released simultaneously with the starting of a material discharge mechanism to permit opening of the bin door for discharge of material.

It is furthermore an object of this invention to provide an ore bin with a counter weighted locking mechanism for the bin door, said mechanism adapted to be controlled by manually operable cables which 50 also govern the operation of a material discharge device connected with one of the cables.

It is an important object of this invention 55 to provide an improved and effective mech-

anism for operating the discharge door of an ore or coal bin.

Other and further important objects of this invention will be apparent from the disclosures in the specification and drawings. 60

The invention (in a preferred form) is illustrated in the drawings and hereinafter more fully described.

On the drawings:

Figure 1 is a side elevation of an ore bin 65 equipped with a door operating and locking mechanism embodying the principles of this invention.

Fig. 2 is a front elevational view of a number of adjacently disposed ore bins 70 equipped with door operating mechanisms.

Fig. 3 is a sectional view taken on line 3—3, of Fig. 2, showing the cylinder in elevation.

Fig. 4 is a sectional view taken on line 75 4—4, of Fig. 1.

Fig. 5 is a section taken on line 5—5, of Fig. 1, with parts omitted.

Fig. 6 is an enlarged view taken on line 6—6, of Fig. 1. 80

As shown on the drawings:

It will be seen that a plurality of ore bins or hoppers may be arranged adjacent one another, as shown in Fig. 2, and separated a sufficient distance to accommodate the door 85 operating and locking mechanisms of this invention. Since the door actuating mechanisms are identical for each of the ore bins, a description of one set of the mechanisms only will be given. 90

The reference numeral 1, indicates the vertical side walls of an ore or coal bin, provided with an inclined bottom or floor 2, the lower end of which terminates within the bin a short distance from the front end 95 thereof. A front wall 3, closes the upper front portion of the bin, and has the lower part thereof directed outwardly and downwardly to form an inclined plate 4, which, together with the side walls 1, forms a discharge chute the end of which is open to afford a discharge opening for ore, coal or any other material carried in the bin. Extending transversely through the lower front portion of the bin is a shaft or axle 5, journaled in the side walls 1, and extending therethrough to permit a large gear 6, to be secured on each projecting end thereof. Secured on the shaft 5, between the side walls 1, is a feeding cylinder or roll 7, disposed to 100 105 100

the front and projecting above the lower edge of the inclined floor 2, as shown in Fig. 3. The cylinder 7, thus located serves as a partial stop for material in the bin.

5 Rotatably mounted to the outside of each of the side walls 1, is an intermediate gear 8, which meshes with its respective large gear 6. Meshing with each intermediate gear 8, is a small driving gear 9, keyed or otherwise secured on a driving shaft 10, journaled in the bin side walls 1. Also secured on each shaft 10, to the outside of the driving gear 9, is a cam friction disk or eccentric roll 11, having a collar 12, integrally formed on the inner side thereof. An arm or lever 13, is integrally formed on each of the collars 12, for the purpose of rotating the respective friction cams. A friction driving roll 14, is mounted on a driving shaft 15, to the outside of each bin side wall 1, in a position to be frictionally contacted by the respective cams 11, when the same are rotated by means of the levers 13. The driving shaft 15, projects transversely through the lower rear portion of the bin and may be connected to any desired source of driving power.

Connected to the free end of each lever 13, is one end of a cable 16, which runs upwardly and forwardly and is supported 30 upon a plurality of rotatable sheaves 17, 18 and 19 respectively mounted on the outer surface of each of the side walls 1. Sheaves 20 and 21, are rotatably mounted on the under side of a horizontal platform 22, disposed to the front of the bin and having the inner edge abutting the inclined front plate 4. Said sheaves 20 and 21, are respectively disposed at the opposite sides of the bin and serve to permit the cable 16, on one side of 40 the bin to be conducted across the front of the bin and connected to the opposite cable 16, to which a stirrup handle 23, is attached, adapted for simultaneously tensioning both of the cables 16, on opposite sides of the bin.

45 Pivottally mounted on the outside of each side wall 1, and near the front edge thereof is the upper end of a locking bar 24, the other end of which is provided with a notch in one corner thereof. Attached to the notched end of each locking bar 24, is one end of a lock cable 25, which is trained around a sheave 26, and has the other end thereof connected to the respective cable 16, on that side of the bin, as shown in Fig. 1.

50 55 A weighted quadrant shaped locking member 27, is pivottally mounted to the outside of each of the side walls 1, below the respective locking bars 24. Each locking member 27, is provided with an angled projection 28, on the curved edge thereof adapted to engage in the notch of the respective locking bar 24. A stop 29, is integrally formed on the weighted inner portion of each locking member. Pivottally attached to each of the locking members 27,

is the upper or inner end of a link or bar 30, the outer or lower end of which is pivotally connected to one side edge of a bin door 31. The door 31, is pivotally supported on the front projecting portions of the side walls, 70 1, and normally closes the discharge opening of the bin. When the door is closed the lower edge thereof is positioned to engage against the feeder cylinder 7. Connected to each locking member at the point of 75 pivotal attachment of the respective link 30, is one end of a door closing cable 32, which is trained around rotatably mounted sheaves 33 and 34, disposed to the inside of the respective sheaves 18 and 19, and shown in 80 dotted lines in Fig. 6. Sheaves 35, are rotatably supported on the under side of the platform 22, adjacent the sheaves 20 and 21, and serve to permit the door closing cable 32, on one side of the bin to be conducted 85 across the front of the bin and secured to the other door closing cable 32, to which a stirrup handle 36, is attached.

The operation is as follows:—

As clearly shown in Fig. 2, each ore or 90 coal bin, is equipped with a duplicate set of mechanisms mounted on opposite sides thereof adapted to be operated simultaneously to equalize the driving and operating stresses applied to the discharge cylinder 95 and the door of each bin. With the parts assembled as shown in Fig. 1, and with the bin filled with ore, coal or any other similar material a truck, dump car or receptacle to be filled with ore is positioned in front of 100 the bin and beneath the door 31 in position to receive ore when the door is opened.

Normally the discharging mechanism and the door operating and controlling means are positioned as shown in full lines in Fig. 105 1, with the door closed. To operate the ore discharging mechanism an operator or attendant takes hold of the handle 23, and pulls downwardly thereon thereby tensioning both of the cables 16, on opposite sides 110 of the bin and causing the levers 13, to swing upwardly into the dotted line position of Fig. 1. This movement of the levers 13, serves to move the cam members 11, into frictional engagement with the rotating 115 driving rolls 14, which are secured on the driving shaft 15. A drive is thus imparted to the small gears 9, the gears 8, and to the large gears 6. Rotation of the gears 6, causes rotation of the feeder cylinder 7. 120 Ore within the bin falls by gravity and rests upon the cylinder 7, which when rotated acts to carry ore over the top thereof against the door 31.

As disclosed in Fig. 1, the locking bars 125 24, are normally positioned to engage the corners 28, of the weighted quadrant members 27, to hold the door 31, locked in closed position. Tensioning of the main cables 16, however, simultaneously tensions the aux- 130

iliary cables 25, connected therewith. The locking bars 24, being connected to the auxiliary cables are thus pulled upwardly out of engagement with the weighted quadrant members 27, which being released permits the force of the ore on the feeder cylinder to move the door 31, outwardly into open position whereby the ore is permitted to be discharged into the car positioned below the door for the purpose. The outward swing of the door 31, is limited by the stops 29, which engage the ends of the locking bars 24. Opening of the door 31, acts to swing the weighted quadrant members 27, forwardly, thereby simultaneously exerting a pull on the cables 32, and causing the handles 36, to move upwardly into the dotted line position as shown in Fig. 1.

When the car below the open door 31, is filled with ore, the handle 23, is released permitting the levers 13, to fall back into normal position and thereby move the cam members 11, out of frictional engagement with the driving rolls 14. The operation of the feeder cylinder 7, is thus discontinued. The operator then pulls downwardly on the handle 36, thereby tensioning both of the cables 32, and swinging the quadrant members 27, rearwardly until the corners 28, thereof engage in the notches of the locking bars 24. The weighted portions of the quadrant members 27, serve to assist in holding and moving the same into normal locking position. With the return of the quadrant members 27, to normal position a pull is exerted on the links 30, which acts to draw the door 31, into closed position thus cutting off any discharge of the ore from the bin.

It will be noted that pulling on the handle 23, acts to simultaneously release the door locking mechanisms and throw the ore discharging means into operation, as well as moving the door closing handle upwardly into the dotted line position of Fig. 1. The locking bars 24, and the controlling quadrant members 27, co-act to hold the door locked in closed position, and also permit opening of the door and limiting of the outward swing thereof. The mechanisms associated with the bin may be conveniently operated by a single operator or attendant.

We are aware that various details of construction may be varied through a wide range without departing from the principles of our invention and we therefore do not purpose limiting the patent granted further than necessitated by the prior art.

We claim as our invention:

1. In an ore bin device of the class described, a bin having a discharge opening therein, a door for closing the opening, an ore discharge mechanism on said bin, a locking mechanism for said door, and means connected with said discharge mechanism and with said locking mechanism for simul-

taneously actuating the same to open the door, and set the discharge mechanism in operation.

2. An ore bin, a door therefor, a locking mechanism for said door, a feeder mechanism connected with said bin, and means connected with said locking mechanism and with said feeder mechanism for simultaneously opening the door and setting the feeder mechanism in operation. 70

3. An ore bin having an opening therein, a door for closing the same, locking means for holding the door locked in closed position, an ore discharge mechanism, means connecting said locking means and said mechanism, and means for tensioning said connecting means for simultaneously releasing said locking means to open the door and starting said mechanism to permit ore to be discharged through said bin opening. 80

4. An ore bin having an outlet opening therein, a door for closing said opening, locking means for holding said door locked in closed position, a driving mechanism, a discharge mechanism, and means connected with said locking means and with said discharge mechanism adapted to be operated to simultaneously release the locking means and throw the discharge mechanism into engagement with the driving mechanism to 95 permit ore to be discharged through said opening.

5. An ore bin having an opening therein, a door for closing said opening, a mechanism for holding said door locked in closed 100 position, a cable connected with said door and mechanism, and handle connected with the cable to tension the same to release the locking mechanism and permit opening of the door. 105

6. The combination with an ore bin having an opening therein, a door for closing said opening, a locking mechanism for holding the door locked in closed position, a cable connected with said locking mechanism, a handle attached to said cable for tensioning the same and causing release of the locking mechanism to permit opening of the door, and means forming a part of the locking mechanism for limiting the 115 opening of the door.

7. The combination with an ore bin door, of a link connected therewith, a pivoted quadrant member connected with said link, a pivoted locking bar releasably engaging 120 said quadrant member to hold the door locked in closed position, a cable connected with said locking bar to permit the locking bar to be moved into release position to permit opening of the door, and a second cable connected with said quadrant member for closing the door and moving the quadrant member into position to be lockingly engaged by said locking bar. 125

8. The combination with an ore bin door, 130

of a link connected therewith, a pivoted member connected with said link, a locking bar releasably engaging said member to hold the door locked in closed position, a cable connected with said bar adapted to be tensioned to move the bar into release position to permit opening of the door, means on said member for limiting the opening of the door, and a second cable connected with 5 said member adapted to be tensioned to close the door and move said member into position to again be lockingly engaged by said bar to hold the door locked.

9. The combination with an ore bin door, 15 of a pivoted member, a link connecting said door with said member, a stop integrally formed on said member, a notched locking bar normally engaging said member for holding the door locked in closed position, 20 a cable connected to said locking bar, a handle on said cable to permit tensioning of the cable whereby said locking bar is moved into release position to permit opening of the door, said stop adapted to contact said locking bar for limiting the opening of said door, and means connected with said member for closing the door and permitting said bar to automatically engage said member to hold the door locked in closed position.

10. The combination with a bin having an opening therein, a door for closing said opening, locking means for the door, a feeder mechanism connected with the bin, a friction drive associated therewith, and 35 flexible means connected with said locking means and with said friction drive adapted to be tensioned to simultaneously release the locking means to open the door

and set the feeder mechanism in operation to permit material in the bin to be discharged 40 through said opening.

11. The combination with a material carrying bin, of a door therefor, a door locking mechanism and a feeder mechanism supported on the bin, and a plurality of connected simultaneously actuatable cables connected with said mechanisms for simultaneously actuating the same to open the door and actuate the feeder mechanism to permit discharge of the material. 50

12. A material carrying bin having an opening therein, a door closing said opening, cable controlled locking means for holding the door locked in closed position, a cable controlled feeder mechanism on said bin connected with said locking means, a handle for releasing said locking means to open the door and starting said mechanism whereby material in said bin is carried to be discharged through the opening, and 55 cable controlled means connected with the locking means for moving the door into closed position to be again locked by said locking means.

In testimony whereof we have hereunto 60 subscribed our names in the presence of witnesses.
